REFRIGERATING APPARATUS

Otto M. Summers, Dayton, Ohio, assignor to General Motors Corporation, Dayton, Ohio, a corporation of Delaware

Application August 13, 1934, Serial No. 739,562
Renewed June 3, 1937

5 Claims. (Cl. 230—206)

This invention relates to refrigerating apparatus and more particularly to a compressor of the reciprocating piston type for a refrigerating machine.

5 In the construction of refrigerating apparatus, it has been customary, heretofore, to provide at the inlet and outlet connections of the compressor manually operable shut-off valves and connections to permit of certain service operations on 10 the refrigerating machine. These valves have, heretofore, been provided as separate units attached either to the compressor or some other part of the refrigerant connections as additional fittings. Also in compressors of the valved piston 15 type, it has been customary to locate the inlet connection in a wall of the crank case inasmuch as the construction requires that incoming gas must enter the crank case.

It is an object of the invention to provide a 20 compressor having both the inlet and outlet connections therefor located in the head of the compressor and to provide in the compressor cylinder head built-in manually operable valves for closing the inlet and outlet connections during service 25 ice operations, as well as to provide in the cylinder head built-in connections to the inlet and outlet for attaching gauges, charging apparatus, purging devices and other accessories utilized in performing service operations.

30 It is also an object to provide a refrigerator compressor of the valved piston type having an inlet connection located in the cylinder head and which communicates with the crank case of the compressor through a built-in conduit formed in 35 the compressor body.

A further object is to provide filtering means in the built-in inlet conduit of the compressor.

Further objects and advantages of the present 40 invention will be apparent from the following description, reference being had to the accompanying drawings, wherein a preferred form of the present invention is clearly shown.

In the drawings:

Fig. 1 is an end view partly in section of a 45 compressor embodying the present invention, the major elements of a complete refrigerating apparatus being shown diagrammatically;

Fig. 2 is a horizontal cross section on line 2—2 of Fig. 1;

50 Fig. 3 is a top view of the cylinder head of the compressor; and

Fig. 4 is a cross section on line 4—4 of Fig. 3.

The refrigerating apparatus disclosed in Fig. 1 55 may comprise preferably a compressor 10 which is adapted to compress gaseous refrigerant for

delivery through a conduit 12 to a condenser 14. The compressed refrigerant is liquefied in the condenser 14 and collected in a receiver 16, whence it is delivered by a conduit 18 to an evaporator 20, which may contain the customary 5 float valve (not shown) for regulating the expansion of liquid refrigerant therein. The conduit 22 delivers gaseous refrigerant to the inlet connection 24 of the compressor 10. A bellows 26 communicates with the conduit 22 to control 10 a switch 28 for intermittently operating a motor 30 which drives the compressor 10 for maintaining substantially constant temperatures in the evaporator 20.

The compressor 10 may comprise a body member 32 forming a crank case and one or more cylinders 34. Two cylinders are disclosed in the present embodiment. Pistons 36 are adapted to be reciprocated in the cylinders 34 by the customary crank shaft and connection rods, well 20 known in the art, and are formed with inlet valves 38 therein for the admission of gas from the crank case to the cylinder. At the top of the body member 32, there is mounted a valve plate 40 forming a seat for an exhaust valve 42 and 25 immediately above the plate 40 there is provided a cylinder head 44, which together with plate 40, is adapted to form a discharge chamber 46 above the valves 42. The head 44 and valve plate 40 and body 32 are formed with apertures which, 30 together, form a conduit 48 communicating with the crank case of the compressor body 32.

A horizontal bore 50 is formed in the cylinder head to communicate with the conduit 48 and inlet connection 24 and to contain a manually 35 operable valve 52. The valve 52 cooperates with a seat member 54 which may be formed at the inner end of the inlet connection 24, while the opposite end of the valve stem is squared at 56 for reception of a suitable tool for operating the 40 valve. A packing gland 58 is provided to seal the valve stem during operation and in order to assure hermetic sealing of the valve operating end of the bore 50 at times when the valve 52 is not in use, a screw plug 60 is provided to seat 45 against the outer face of the cylinder head by means of a gasket 62. An additional bore 64 (see Fig. 2) is formed in the cylinder head communicating between the bore 44 and the outside of the head. It is normally closed by a screw plug 66. 50 A second bore 68 is formed in the cylinder head for the reception of a manually operable valve 70 adapted to cooperate with a seat formed on the inner end of an outlet connection 72. A 55 packing gland 74 and sealing plug 76 are provided

in the same manner as for the valve 52. Also, an additional bore 78 communicates between the bore 68 and the outside of the head and is normally closed by a screw plug 80. The bore 68 communicates with the discharge chamber 46 as shown in Fig. 4 at 82. Each of the valves 52 and 70 is provided with a back seat 84 and 86 respectively for closing communication between the bores 50 and 68 and the connections 24 and 72 respectively when the valves are in open position.

In operation, the valves normally lie in the positions shown in Fig. 2 in which refrigerant is circulated through the inlet connection 24 and valve 52 to the conduit 48 and the crank case of the compressor. Gas discharged into the chamber 46 passes through the passage 82, and valve 70 to the connection 72. During normal functioning of the refrigerating apparatus, the operation is as just described.

Upon occasions when it becomes necessary to perform service operations on the refrigerating apparatus, the plugs 66 and 80 may be removed to attach gauges or other service accessories and when attached communication may be established with the rest of the system by removing either or both of the plugs 60 and 76 and moving the valves 52 and 70 to a position midway between the two seats therefor. Also if for any reason, it is desired to shut off communication between the compressor and either the exhaust conduit 12 or the intake conduit 22, either the valve 70 or the valve 52 may be completely closed.

It will thus be seen that there has been provided a compressor in which the necessary manual intake and discharge valves are provided as built-in parts of the compressor, and that not only the discharge valve, but the intake valve as well are located at the cylinder head. This contributes materially to a neat appearance of the complete refrigerating apparatus and eliminates a considerable number of detachable connections otherwise necessary.

While the form of embodiment of the invention as herein disclosed, constitutes a preferred form, it is to be understood that other forms might be adopted, all coming within the scope of the claims which follow.

What is claimed is as follows:

1. In a refrigerator compressor of the reciprocating valved piston type, the combination of a

compressor body forming a cylinder and a crank case, a cylinder head, an inlet connection in said cylinder head and means forming a conduit from said inlet connection to the crank case for conducting all incoming gas to the crank case through the cylinder head and the compressor body.

2. In a refrigerator compressor of the reciprocating valved piston type, the combination of a compressor body forming a cylinder and a crank case, a cylinder head, an inlet connection in said cylinder head, means forming a conduit from said inlet connection to the crank case for conducting all incoming gas to the crank case, and a manually operable valve in the cylinder head for at times closing said inlet connection.

3. In a refrigerator compressor of the reciprocating valved piston type, the combination of a compressor body forming a cylinder and a crank case, a cylinder head, an inlet connection in said cylinder head, means forming a conduit from said inlet connection to the crank case for conducting all incoming gas to the crank case, a manually operable valve in the cylinder head for at times closing said inlet connection, a bore in the cylinder head communicating between said conduit and the outside of the compressor, and means for closing the outer end of said bore.

4. In a refrigerator compressor of the reciprocating valved piston type, the combination of a compressor body forming a cylinder and a crank case, a cylinder head, an inlet connection in said cylinder head and means forming a conduit from said inlet connection to the crank case extending through the cylinder head and the compressor body for conducting all incoming gas therethrough to the crank case, and a manually operable valve in the cylinder head for at times closing said inlet connection.

5. In a refrigerator compressor of the reciprocating valved piston type, the combination of a compressor body forming a cylinder and a crank case, a cylinder head, an inlet connection in said cylinder head, an outlet connection in said cylinder head, means forming a conduit from said inlet connection to the crankcase for conducting all incoming gas to the crankcase, a reciprocating piston compressing gas from said crankcase and discharging compressed gas through said outlet connection.

OTTO M. SUMMERS.
